UNITED STATES PATENT OFFICE.

PHILIP GAUSS, OF NEW YORK, N. Y.

BOTTLE-NIPPLE.

SPECIFICATION forming part of Letters Patent No. 705,916, dated July 29, 1902.

Application filed July 18, 1901. Serial No. 68,782. (No model.)

To all whom it may concern:

Be it known that I, PHILIP GAUSS, a citizen of the United States, and a resident of the city of New York, borough of Manhattan, in 5 the county and State of New York, have invented a new and Improved Bottle-Nipple, of which the following is a full, clear, and exact description.

This invention relates to improvements in 10 nipples for nursing-bottles; and the object is to provide a nipple having that portion of it designed for a mouthpiece non-collapsible, so that the opening or duct through it cannot become closed by external pressure or by 15 vacuum occurring in the bottle.

I will describe a bottle-nipple embodying my invention and then point out the novel features in the appended claim.

Reference is to be had to the accompanying 20 drawings, forming a part of this specification, in which similar characters of reference indicate corresponding parts in all the figures.

Figure 1 is a longitudinal section of a bottle-nipple embodying my invention. Fig. 2 25 is a section on the line 2 2 of Fig. 1, and Fig. 3 is a section on the line 3 3 of Fig. 1.

The nipple comprises a mouth portion 5 and a portion 6, designed to be engaged over the neck of the bottle. This portion 6, therefore, 30 is made sufficiently elastic to stretch over the bottle-neck. The mouth portion, however, is made practically hard or non-collapsible—that is, it is sufficiently hard to prevent its being pressed inward to close the opening or

duct 7. It will have a slight yield, however, 35 in a child's mouth. The duct 7 is made quite large and has a reduced portion with outlets 8. This duct, it will be observed, is straight from end to end, or, in other words, its walls have no longitudinal curves, and therefore 40 the nipple may be readily cleaned by means of a brush or other similar device. The mouth-piece is made oval in cross-section, adapting it for a child's mouth, and, further, by making it in this form the walls at the approximately flat sides are thinner than at the other sides, so as to give a proper degree of elasticity, but collapsing will be prevented by the thicker wall portions.

Having thus described my invention, I 50 claim as new and desire to secure by Letters Patent—

A nursing-bottle nipple having a mouth-piece provided with a straight cylindrical duct through it and reduced outlets, the said mouth-piece being oval in cross-section, the walls at the approximately flat sides being thinner than the walls at the other sides, whereby the thin walls will permit of slight yielding and the thicker walls will prevent collapsing. 55

In testimony whereof I have signed my name to this specification in the presence of two subscribing witnesses.

PHILIP GAUSS.
